EVAPORATIVE COOLER PAD FRAME
CONSTRUCTION

Adam D. Geelti, Phoenix, Ariz., assignor to McGraw-Edison Company, Elgin, Ill., a corporation of Delaware
Filed July 7, 1958, Ser. No. 747,824
4 Claims. (Cl. 261—97)

This invention relates to an evaporative cooler pad frame construction and more particularly to an evaporative cooler pad frame construction having novel features for removably supporting an evaporative cooler pad in spaced relation to air inlet louvers of an evaporative cooler whereby water which gravitates through the evaporative cooler pad does not contact the louvers and permit them to become encrusted with mineral salts.

In the operation of evaporative coolers water is elevated to the upper portions of evaporative cooler pads by a pump or water pressure whereupon the water is distributed over the upper surface of the pad and permitted to gravitate downwardly therethrough. A blower is usually provided to force air through an evaporative cooler pad and the air enters the cooler through a louvered plate in the side wall thereof preliminary to its passage through the pad. In conventional evaporative coolers the pad is placed adjacent or contiguous to the louvered plate and water passing downwardly through the pad wets the louvers of the plate. Minerals in the water collect on the louvers of the plate and form a thick crust which eventually reduces air flow efficiency through the louvers and also causes an undesirable appearance of the louvers externally of the cooler.

It has been a problem to provide an evaporative cooler pad frame construction which readily permits the pads to be removed and yet operated in spaced relation with a louvered plate whereby the plate does not become encrusted with mineral salts from water passing downwardly through the evaporative cooler pad adjacent thereto.

Accordingly, it is an object of the present invention to provide a novel evaporative cooler pad frame construction wherein an evaporative cooler pad is readily removable from an evaporative cooler and wherein the pad is maintained in spaced relationship with an air inlet louver plate thereby preventing the plate from becoming encrusted with mineral salts during operation of the evaporative cooler.

Another object of the invention is to provide a novel evaporative cooler pad frame construction wherein a trough and pad retaining screens are arranged in a unitary assembly with an evaporative cooler pad.

Another object of the invention is to provide novel means for removably retaining an evaporative cooler pad and trough assembly in the frame of an evaporative cooler.

Another object of the invention is to prevent louver plates at the outer sides of evaporative coolers from becoming encrusted with mineral salts.

Another object of the invention is to provide an evaporative cooler pad frame construction which maintains an evaporative cooler pad in unitary assembly with a water distributor whereby the entire assembly may be removed from the frame of an evaporative cooler for maintenance service and pad replacement.

Further objects and advantages of the invention may be apparent from the following specification, appended claims and accompanying drawings in which:

FIG. 1 is a fragmentary, vertical, sectional view of an evaporative cooler showing an evaporative cooler pad frame construction of the present invention installed therein.

FIG. 2 is a fragmentary, plan, sectional view taken

2

from the line 2—2 of FIG. 1 showing parts and portions in elevation to facilitate the illustration.

FIG. 3 is a fragmentary, sectional view taken from the line 3—3 of FIG. 1.

FIG. 4 is a fragmentary, vertical, sectional view of an evaporative cooler showing the modified form of an evaporative cooler pad frame construction in accordance with the present invention.

FIG. 5 is a fragmentary, plan, sectional view taken from the line 5—5 of FIG. 4.

FIG. 6 is a fragmentary, vertical, sectional view of a further modified form of an evaporative cooler pad frame construction in accordance with the present invention showing parts and portions in elevation to facilitate the illustration.

FIG. 7 is a fragmentary, sectional view taken from the line 7—7 of FIG. 6.

FIG. 8 is a fragmentary, sectional view taken from the line 8—8 of FIG. 6 and

FIG. 9 is a fragmentary, sectional view taken from the line 9—9 of FIG. 6.

As shown in FIG. 1 of the drawings an evaporative cooler sump 10 is disposed to receive water which drains from evaporative cooler pads positioned thereabove. The sump 10 supports corner frame elements 12 of an evaporative cooler frame. These corner frame elements are provided with vertical recess tracks 14 which receive flanged edges 16 of a louver plate 18 at one outer side of an evaporative cooler. As shown in FIG. 1 of the drawing an upper edge 20 of the louver plate 18 is disposed inwardly of a top skirt 22 of an evaporative cooler whereby the upper portions of the flanges 16 are retained in the tracks 14.

The lower edge 24 of the louver plate 18 is disposed inwardly of the sump pan 10 and is provided with a folded portion terminating in a hook shaped member 26 which is hooked over a normally upper edge 28 of the sump pan 10. Thus, the louver plate 18 is supported in the side wall of a conventional evaporative cooler frame.

The louver plate is provided with open louvers 30 through which air may pass inwardly into the interior of an evaporative cooler toward a foraminous evaporative cooler pad 32. This pad 32 may be made of wood excelsior or other suitable material and is provided with an inner layer 34 of fine glass fibers or other suitable material which will act as a filter to catch dust, insects and other foreign matter thereby preventing it from being carried in the air stream passing through the pad. The pad 32 and filter 34 are contiguous with each other and retained between foraminous pad retainers 36 and 38. These pad retainers 36 and 38 are wire mesh screen structures having inwardly projecting members 40 and 42 respectively which extend into the pad and vertically support the same between the retainers 36 and 38. These pad retainers are provided with vertical bars 44 and 46, respectively, and horizontal bars 48 and 50, respectively. These bars are spot welded together and the projecting members 40 and 42 are welded at the juncture of the vertical and horizontal bars thereby providing rigid durable pad supports. The pad retainer 36 is provided with an uppermost horizontal bar 52 which is pivotally retained in a hook shaped clip channel portion 54 integral with one side of a water distributor trough 56 above the pad 32. The opposite side of the trough 56 is provided with another hook shaped portion 58 which pivotally retains a horizontal bar 60 at the upper edge of the pad retainer 38.

The trough 56 may be molded of plastic or may be made of sheet metal if desired. The upper horizontal bars 52 and 60 of the pad retainers 36 and 38 are pivotally retained in the hook shaped clip portions 54 and 58 and due to the resilience of these hook shaped portions

70

54 and 58 the bars 52 and 60 may be forced thereinto by lateral deflection of the hook shaped portions 54 and 58. Thus, these horizontal bars 52 and 60 are snapped into the hook shaped clips 54 and 58 and are hingedly supported thereby.

The lower ends of the pad retainer screen 36 and 38 are provided with horizontal bars 62 and 64, respectively, which are engaged and held by hook shaped portions 66 and 68, respectively, of a bottom member 70 at the lower end of the pad 32. This member 70 is substantially channel shaped and provided with openings 72 therein to provide for drainage of water downwardly away from the pad 32. Secured to the bottom member 70 is an air baffle 74 which extends into close proximity to one of the louver vanes 30 in order to minimize the passage of air between the louvers 30 and the pad 32 at the outer lower portion thereof.

The upper and lower bars 60 and 64, respectively, of the pad retainer screen 38 form trunnions at their ends which are disposed in slots 76 and 78, respectively, of sheet metal plates 80 which extend inwardly from the recessed troughs 14 of the cooler frame corner elements 12 as shown best in FIGS. 1 and 2 of the drawing. It will be seen that the trunnion ends of the bars 60 and 64 project a short distance through the plates 80 and that these plates are provided with joggled portions 82 which are offset a greater distance than the outward extension of the bars 60 and 64 so that they may be removed together with the trough 56 and pad 32 from the cooler between the track portions 14. The plates 80 may be deflected outwardly from the pad 38 so that the trunnion ends of the bars 60 and 64 may be cleared from the slots 76 and 78.

It will be seen that the louver plate 18 as hereinbefore described must be raised vertically whereupon the upper edge 20 of the louver plate passes upwardly behind the skirt 22 while the vertical edges 16 ride upwardly in the tracks 14 until the lower edge 24 of the louver plate clears the upper edge 28 of the sump pan 10. The louver plate 18 may then at its lower edge be moved outwardly and downwardly until the upper edge 20 thereof clears the skirt 22 whereupon the louver plate 18 may be removed from the side of the evaporative cooler. This provides access for the removal of the evaporative cooler pad assembly which includes the trough 56, pad retainer screens 36 and 38 together with the pad 32 and filter 34.

The louver plate 18 is provided with a baffle 84 at its upper edge which is fitted adjacent to the hook shaped clip portion 54 of the trough 56 to prevent leakage of air between the pad 32 and the louver plate 18. This baffle is removed together with the louver plate 18 when it is disassembled from the cooler frame as hereinbefore described. The baffle 74 is carried by the bottom member 70 of the evaporative cooler pad assembly as hereinbefore described.

As shown in FIG. 1 of the drawings the inner edges 86 of the louver vanes 30 are spaced from the foraminous pad retainer screen 36 thereby preventing any of the excelsior or other material of the pad 32 from engaging these inner edges 86. Thus, water which passes downwardly through the pad 32 does not contact the louver vanes 30 whereby they are maintained in dry, clean condition. This spacing of the pad from the louver vanes prevents them from getting wet and accumulating deposits of mineral salts which are normally carried in water used to wet the pad 32.

In operation water is delivered into the trough 56 by means of a conduit having water therein under pressure and the water drains downwardly from the bottom of the trough through perforations 57 into the pad 32. Air is forced through the open louvers 30 and the pad 32 and filter 34 as indicated by arrows in FIG. 1 of the drawings. This causes evaporation of water in the pad and consequent cooling of the air which passes therethrough. The water passing downwardly through the

pad 32 does not contact the louver vanes 30 due to a spaced relation of the edges and the pad retainer frame 36 as hereinbefore described. The excess water passes downwardly through openings 72 and into the sump pan 10 from which it is recirculated by a pump or from which it may be drained off as desired.

When from time to time it is desired to replace the pad 32 and filter 34 the louver plate 18 is removed as hereinbefore described and the evaporative cooler pad assembly is also removed from the plates 80 of the evaporative cooler frame as hereinbefore described. The bottom member 70 of the evaporative cooler pad assembly is disengaged from the bars 62 and 64 by forcing them together and removing them from the hooked shaped portion 66 and 68 of the bottom member 70. This operation causes slight compression of the pad 32 and filter 34 and when the bottom member 70 is thus removed from the bars 62 and 64 the retainer screens 36 and 38 may be hingedly moved apart so that the projecting bars 40 and 42 of the retainers 36 and 38 may be disengaged from the pad 32 and filter 34 thereby permitting their removal from the retainers 36 and 38.

A fresh pad and filter may be inserted between the retainers 36 and 38 whereupon they may be pivoted toward each other about the axis of their bars 52 and 60 which are hingedly and pivotally mounted in the hook shaped portions 54 and 58 of the trough 56. When the retainers 36 and 38 are pivoted toward each other the bars 40 and 42 thereof are forced to pierce the pad 32 and filter 34 and extend therewith. When the retainer screens 36 and 38 are forced together at opposite sides of the pad 32 and filter 34 the bottom member 70 at its clip portions 66 and 68 is engaged with the lower bars 62 and 64 of the retainer screens 36 and 38 and compression of the pad 32 and filter 34 maintains the bars 62 and 64 in engagement in the hook shaped clip portions 66 and 68 of the bottom member 70.

In the modification as shown in FIGS. 4 and 5 a pad frame 90 carries a louver plate 92, a trough 94, a pad 96 and supporting retainer screens 98 and 100. This entire assembly carried by the pad frame 90 is removable from the cooler frame elements 12 in a similar manner to that of the louver plate 18 hereinbefore described and disclosed in FIGS. 1 to 3, inclusive. Thus, the pad frame structure shown in FIGS. 4 and 5 of the drawings maintains the louver plate 92 integral with the pad supporting assembly.

Folded over the upper edge of the louver plate 92 is a plate 102 which is formed to provide the trough 94 disposed above the pad 96. Integral with the hook 26 is a bottom member 104 which is folded over the lower edge of the louver plate 92 to form a bottom structure for supporting the pad 96. As shown in FIG. 5 of the drawings vertical edges of the louver plate 92 are folded 55 and extend backwardly into side plates 106 of the pad frame 90. Secured on the inner sides of these side plates 106 are angle members 108 which are spaced backwardly from the edges 110 of louvers 112 similar to the louvers 30 hereinbefore described. Engaging the 60 angles 108 is a pad retaining screen 114 disposed in spaced relationship with the edges 110 of the louver vanes 112. Inwardly of the retainer 114 is the pad 96 and a contiguous filter layer 116.

A retainer screen 118 engages the filter layer 116 in 65 spaced relationship to the retainer screen 114 and each opposite edge of the retainer screen 118 is held by a flange 120 of each side plate 90.

The retainer screen 118 is held by a conventional clip bar 122 having hooks 124 on its opposite ends which are engaged in openings 126 in the side plates 90. The pad retaining screens 114 and 118 are provided with horizontal bars 119 and 121 which extend into the pad 96 and filter 116 and these horizontal bars are secured to the vertical and horizontal bars, respectively, of the 70 pad retaining screens 114 and 118.

In operation the evaporative cooler pad frame construction as shown in FIGS. 4 and 5 prevents the louver vanes 112 from becoming encrusted due to the spacing of the pad 96 therefrom by the screen retainer 114 which is held in the pad frame 90 by the angle members 108.

When it is desired to replace the pad 96 and filter 116 the louver plate 92 together with the pad frame 90, trough 94, pad 96 and screen frames 98 and 100 are all removed in one unit as hereinbefore described whereupon the hooks 124 of the bars 122 are disengaged from the openings 126 whereupon the retainer screen 118 may be removed permitting replacement of the pad 96 and filter 116.

In the modification as shown in FIGS. 6 to 9, inclusive, of the drawings a louver plate 130 is removably supported in the cooler frame in substantially the same manner as the louver plate 18 disclosed in FIGS. 1 to 3 of the drawings. The louver plate 130 is provided with louver vanes 132 having inner edges 134 and the upper edge of the louver plate is engaged by a folded member 136 having an integral extending plate portion 138 which interconnects side plates 140 integral with folded edges 142 which correspond with the folded edges 16 of the structure shown in FIGS. 1 to 3 of the drawings.

Connected with the louver plate 130 at its lower edge is the bottom plate 144 which is folded over the lower edge of the louver plate 130 and integral with the hook 26. The bottom plate is provided with openings 146 to permit drainage of water from the evaporative cooler pad into the sump 10.

Positioned between the side plates 140 is a pad assembly including a pair of spaced plates 148, which are contiguous with the plates 140 and, on which a trough 150 is supported. The trough 150 is carried by flanges 152 at the upper portions of the plates 148. These plates 148 are provided with spaced flanges 154 and 156 adjacent to which retainer screens 158 and 160, respectively, are positioned. These retainer screens 158 and 160 support an evaporative pad 162 and a filter pad 164 between the plates 148. These plates 148 are provided with fixed pins 166 which project through slots 168 in the side plates 140 as shown best in FIGS. 6 and 9 of the drawings. The opposite ends of trough 150 rest in slots 170 in the side plates 140 as shown best in FIGS. 6 and 7 of the drawings. The trough 150 is provided with water outlet nozzles 172 which permit water to drain downwardly through the pad 162. Hook bars 174 interconnect the flanges 156 and these hook bars 174 are similar to the bars 122 hereinbefore described in connection with FIGS. 4 and 5 of the drawings.

In operation the louver plate 30 when removed from the cooler frame carries with it the side plates 140 in which are secured the plates 148, trough 150, pad 162, filter 164 and the pad retaining screens 158 and 160. When removed from the evaporative cooler frame the plates 140 may be removed from the plates 140 apart to permit the ends of the pins 166 to clear the slots 168. The trough 150 at its opposite ends may then be removed from the slots 170 in the plates 140.

The pads 160 and filter 140 may be then replaced as hereinbefore described in connection with the replacement of the pads shown in FIGS. 4 and 5 of the drawing.

It will be obvious to those skilled in the art that various modifications of the present invention may be resorted to in any manner limited only by a just interpretation of the following claims.

I claim:

1. In an evaporative cooler pad frame construction the combination of: an evaporative cooler frame having vertically disposed spaced pad frame plates; a water trough

overlying a space between said plates; a pair of foraminous pad supports below said trough and disposed in spaced relationship with each other; one of said pad supports hinged to said trough; a foraminous pad between said pad supports and below said water trough, means holding the lower ends of said pad supports in engagement with opposite sides of said pad; and means removably supporting said trough, pad supports and pad on and between said pad frame plates.

5 2. In an evaporative cooler pad frame construction the combination of: an evaporative cooler frame having vertically disposed spaced pad frame plates; a water trough overlying a space between said plates; foraminous pad supports hinged to and depending from said trough and disposed in spaced relation to each other; a foraminous pad between said pad supports; and below said water trough; means holding the lower ends of said pad supports in engagement with opposite sides of said pad; and means removably supporting said pad supports and pad on and between said pad frame plates; and a louvered plate supported on said cooler frame outwardly of said pad in spaced relation thereto whereby water which gravitates from said trough through said pad does not contact said louvered plate.

10 3. In an evaporative cooler pad frame construction the combination of: an evaporative cooler frame having vertically disposed spaced pad frame plates; a water trough overlying a space between said plates; foraminous pad supports hinged to and depending from said trough and

20 disposed in spaced relation to each other; a foraminous pad between said pad supports and below said water trough; means holding the lower ends of said pad supports in engagement with opposite sides of said pad; and means removably supporting said pad supports and pad

30 on and between said pad frame plates; and a louvered plate supported on said cooler frame outwardly of said pad in spaced relation thereto whereby water which gravitates from said trough through said pad does not contact said louvered plate, said foraminous pad supports being

35 40 of wire mesh construction and having trunnion portions, said frame plates having openings receiving said trunnions thereby supporting said pad in said cooler frame.

4. In an evaporative cooler pad frame construction the combination of: an evaporative cooler frame; a pad frame

45 in one side thereof; louvers in the outer side of said pad frame; and a water distributor and pad assembly removably mounted in said pad frame and spaced from said louvers, said assembly comprising a pair of plates, spaced screens held therebetween; a foraminous pad between said

50 screens and a water distributor supported on said plates and disposed above said foraminous pad, said pad frame having openings therein; and trunnions fixed to said plates and disposed in said openings, said pad frame being of resilient material whereby it may be deflected beyond the 55 ends of said trunnions.
